(57) **CLAIM**

The ornamental design for a plugs with adjustable metal baffle for LED light strips, as shown and described.

DESCRIPTION

FIG. 1 is a perspective view of a plugs with adjustable metal baffle For LED light strips showing my/our new design;

FIG. 2 is a front view thereof;

FIG. 3 is a top view thereof;

FIG. 4 is a back view thereof;

FIG. 5 is a bottom view thereof;

FIG. 6 is a right side view thereof;

FIG. 7 is a left side view thereof;

FIG. 8 is an enlarged view of portion 8 shown in FIG. 1;

FIG. 9 is an enlarged view of portion 9 shown in FIG. 1; and, FIG. 10 is an enlarged view of portion 10 shown in FIG. 1. The broken lines in the drawings illustrate boundaries of the design and form no part of the claimed design.

The break lines in the drawings indicate that the appearance of any portion of the plugs with adjustable metal baffle for LED light strips, between the break lines forms no part of the claimed design.
